UNITED STATES PATENT OFFICE

133,220

DESIGN FOR A BOWLING BALL RACK FOR BOWLING ALLEYS

Alfred Reiss, Newton, Mass.

Application December 26, 1941, Serial No. 104,868

Term of patent 7 years

To all whom it may concern:

Be it known that I, Alfred Reiss, a citizen of the United States, residing at Newton, in the county of Middlesex and State of Massachusetts, have invented a new, original, and ornamental Design for a Bowling Ball Rack for Bowling Alleys, of which the following is a specification, reference being had to the accompanying drawing, forming part thereof.

Figure 1 is a perspective view of a bowling ball rack, showing my new design. Figure 2 is a top plan view and Figure 3 is an end elevational view.

I claim:

The ornamental design for a bowling ball rack for bowling alleys, as shown.

ALFRED REISS.
